APPARATUS FOR RECLAIMING SOLVENT

Russell A. Hetzer, Cincinnati, Ohio, assignor to
The American Laundry Machinery Company,
Cincinnati, Ohio, a corporation of Ohio

Original application June 18, 1930, Serial No.
462,061. Divided and this application April 3,
1935, Serial No. 14,456

3 Claims. (Cl. 68—18)

My invention relates to dry cleaning systems which utilize a volatile solvent as the detergent, and more particularly to an apparatus for removing the foreign matter from the detergent after the treating operation, whereby the same detergent may be employed in subsequent operations. This application is a division of application Ser. No. 462,061, filed January 18, 1930 now Patent No. 2,041,711.

10 The method of treating fabric in dry cleaning systems consists in employing a solvent having a low boiling point, such as carbon tetrachloride, and agitating the fabric with a pool of solvent to remove the dirt and foreign matter from the fabric and cause its transfer to the solvent. The used solvent is then drained into a sump tank or collecting vessel. In such systems it is desirable to repeatedly use the same solvent or detergent and to have it equally effective in each operation, 20 and consequently, means including a condenser and evaporator are provided to renovate the used solvent.

In accordance with my invention I have provided automatic means for withdrawing solvent 25 from the sump tank or collecting vessel when the solvent therein has attained a predetermined level, and automatic means for regulating the amount of heat supplied to the evaporator.

It is therefore an object of my invention to 30 provide an improved reclaiming apparatus by means of which solvent may be forced into an evaporating apparatus when the solvent has attained a predetermined level in the sump tank or collecting vessel. Another object of my invention 35 is to provide improved means for regulating the supply of heating medium to the evaporator, depending upon the amount of solvent which is to be vaporized. A further and more specific object of my invention is to provide improved means 40 for controlling the action of a motor to pump solvent from the collecting vessel or sump tank when the liquid has attained a predetermined level, and means for regulating the amount of heat supplied to the evaporator.

45 My invention will be better understood by reference to the accompanying drawing, in which Fig. 1 is a diagrammatic view of my improved apparatus, and Fig. 2 is an enlarged diagram of the switch and its operating parts.

50 As illustrated in the drawing, my improved renovating apparatus is shown as applied to a washer or treating vessel or tub 1 which is provided with the usual rotatable work containing drum 2. The washer is provided with conduits 3 and 4 by means of which suitable apparatus may

be connected to it for drying and deodorizing the fabric, as illustrated in my copending application. A storage tank 5 is mounted at a higher level than the treating vessel 1 and contains a supply of volatile liquid to be utilized in the treating operation. A conduit or pipe 6 connects the bottom of the storage tank 5 with the treating compartment 1 and is provided with a valve 7 regulating the amount of treating medium which passes from the storage tank to the treating compartment.

To prevent any water or moisture which may collect and float on the surface of the treating medium from gravitating into the treating compartment 1 through the conduit 6, the conduit 6 15 extends into the tank and is provided with two branches 8 and 9. The branch 8 extends upwardly to a point above the level of the treating medium within the storage tank and the branch 9 is in the form of a 90° elbow having its lower end 20 but slightly above the bottom of the tank 1. The solvent which is supplied to the treating vessel through the conduit 6 will therefore always flow from the lowermost part of the storage tank. When valve 7 is open for supplying solvent to the 25 treating compartment 1, the treating medium will drain from the storage tank 5 until it has reached a level which is slightly below the point of connection of the branch 8 with the branch 9. At this point the flow of treating medium will stop. 30 As the level of solvent in the storage tank can never drop to the point of the opening of the branch 9, water or moisture floating on the surface of the treating medium will not be drained into the treating compartment.

A drain conduit 10 provided with a valve 11 35 leads from the bottom of the treating compartment 1 to the sump tank 12 located below the compartment. Filter means 12a are provided at the delivery end of the conduit 10 for separating 40 particles of foreign matter.

In renovating the used treating material, it is first drawn from the sump tank 12 by means of a pump 13. The intake side of the pump is connected to the sump tank 12 by means of a conduit 14 which is provided with a branch conduit 15 controlled by a valve 16. Conduit 15 terminates in a free end to provide a pipe or hose connection. The conduit 14 is also provided with a control valve 17 for regulating the flow of 45 medium from the sump tank 12 to and through the pump 13. The valve 17 is normally open and the valve 16 is normally closed. However, when a fresh supply of treating medium from some outside source is to be supplied to the apparatus, the 50 55

valve 17 is closed and the valve 16 is opened at which time a pipe or hose may be attached to the pipe connection 15 and a fresh supply of medium may be drawn into the apparatus by the 5 operation of the pump 13.

As illustrated in the drawing, the portion of the pipe 14 extending within the sump tank 12 terminates in a vertically extending T-connection, the upper end 18 of which is adjacent the 10 top of the sump tank and the lower end 19 of which is adjacent the bottom thereof. By utilizing a T-connection of this type the solvent may be withdrawn from the sump tank adjacent the bottom thereof and means are also provided for 15 maintaining a minimum amount of solvent in the sump tank, the amount being determined by the point where the conduit 14 joins conduits 18 and 19.

As a first step in the circulation of the treating medium from the sump tank 12 the medium is 20 passed into a filter 20 by way of a conduit 21 leading from the discharge side of the pump 13, the conduit being controlled by the valve 22. A pipe or conduit 23 under control of valve 24 leads 25 from conduit 21 and terminates in a pipe or hose connection. Normally when the apparatus is in operation valve 24 is closed and valve 22 is open. However, if for any reason it is necessary to 30 empty the system of the treating medium, the valve 22 is closed, the valve 24 is opened and a suitable hose or pipe is attached to the connection 23, whereby the solvent may be discharged from the system.

The filter 20 comprises a cylindrical outer shell 35 25 and a filter bag 26. Conduits 27, 28 controlled by valves 29 and 30 connect the exterior and inner portion of the filter with the sump tank through the conduit 14. Means are thereby provided for draining the filter when necessary or desirable.

A pipe or conduit 31 connects the filter to a 40 main evaporator 32 and a branch pipe 33 under control of a valve 34 connects the filter shell with the storage tank 5 through a portion of the pipe 31. The pipe 31 is provided with a check valve 35 to prevent liquid from flowing backwardly from the evaporator 32 into the filter.

An auxiliary evaporator 36 is also provided which is connected to the main evaporator 32 by means of a conduit 37 which is controlled by the valve 38. The auxiliary evaporator is provided so that sludge collecting in the bottom of evaporator 32 may be drained into the auxiliary evaporator in desired amounts or at desired intervals and the solvent recovered from the sludge. 50 It will be noted that by such an arrangement the solvent may be recovered from the sludge without discontinuing evaporation in the main vaporizer. A conduit 67 controlled by valve 68 is provided for draining the sludge from the auxiliary evaporator after substantially all of the solvent has been removed.

The vapors from evaporators 32 and 36 are passed to condenser 39 through conduits 40 and 41 and the condensate flows through conduit 42, filter 43 and conduit 44 into the storage tank. 65 Conduits 45 and 46 are provided for circulating a suitable cooling fluid through the condenser.

In accordance with my invention I have provided automatic means for controlling the operation 70 of the motor 48 which controls the action of pump 13 when the level of the liquid in the sump or collecting tank 12 attains a predetermined level and also means for controlling the supply of heating medium to the evaporators so that the evaporating process may be expedited after 75

the evaporators have been supplied with a fresh quantity of the solvent to be vaporized.

As illustrated in the drawing, current is supplied to the motor from lines L1 and L2 which are controlled by switch 50. Steam is supplied 5 to evaporators 32 and 36 by a main supply pipe 52 which is controlled by valve 53. Switch 50 preferably is any suitable form of snap switch capable of float control. As conventionally illustrated, the switch includes a switch arm 54 biased 10 in either open or closed position by a spring 62 and having an operating arm 63 actuated by lugs 54 on a rod 55 connected to a float 56 which rests upon the surface of the liquid in the sump tank 12. The rod 55 extends through an aperture 15 in the top of the tank 12 and is also provided with a pair of spaced lugs 57 and 58 which operate the handle 59 of valve 53. When the level in the sump tank 12 falls a predetermined amount the switch opens and when the level of liquid 20 in the sump tank rises to a predetermined level the switch closes. After a predetermined amount of solvent has been forced into the evaporator the lug 58 opens the valve 53 to supply heating medium to evaporators 32 and 36 through supply 25 pipe 52 and branch pipes 60 and 61. As the sump fills up, reverse operations of switch 50 and valve 53 are produced.

The operation of my improved apparatus will now be apparent. The liquid is first drained from 30 the treating vessel 1 into the sump tank 12. After a predetermined amount of solvent has collected in the sump tank the float 43 which rises with the liquid closes the switch 50. The closing of switch 50 supplies current to motor 48 which 35 operates pump 13, thereby forcing liquid into the main evaporator 32 and by operating valve 38 solvent containing sludge is drained into auxiliary evaporator 36. As the level of the liquid in tank 12 falls the lug 58 engages handle 59 of valve 53 40 and heating fluid, such as steam, is supplied to the evaporators 32 and 36 through main conduit 52 and branch conduits 60 and 61. As the solvent rises in the tank, however, the lug 57 again makes contact with handle 59 of valve 53 45 and the supply of steam is diminished or entirely cut off. It will be understood that in accordance with my invention a small amount of steam may be continuously supplied to the evaporators 32 and 36 and that when a fresh supply of solvent is pumped into the evaporators the supply of steam may be materially increased.

From the foregoing specification it will be apparent that I have provided an improved apparatus by means of which solvent may be automatically forced into the evaporators when the quantity of liquid in the sump tank reaches a predetermined level.

It will also be seen that by my improved apparatus the amount of heating medium such as 60 steam which is utilized to evaporate the solvent may be increased or diminished in accordance with the amount of liquid which is to be evaporated. By utilizing my improved system it will therefore be understood that the reclaiming of 65 the solvent may be automatically controlled.

To those skilled in the art many modifications and widely different embodiments of my invention will suggest themselves without departing from the spirit and scope thereof. My disclosure 70 and description are purely illustrative and are not in any sense limiting.

What I claim is:

1. An apparatus for reclaiming used solvent, comprising a sump tank to which the used solvent 75

- is intermittently supplied, an evaporator, said sump tank and evaporator forming a closed circuit with a condenser and treating vessel, means for conducting solvent from said sump tank to 5
6 said evaporator, means for forcing solvent through said conducting means from said sump tank to said evaporator, means for supplying heat to said evaporator, means responsive to the fall of liquid in said sump tank to a predetermined level for 10
10 increasing the supply of heat to said evaporator, and means responsive to the rise of liquid in said sump tank to a predetermined level for decreasing the supply of heat to said evaporator, whereby the supply of heat to said evaporator is accommodated to the supply of solvent thereto.
2. An apparatus for reclaiming used solvent, comprising a sump tank to which the used solvent is intermittently supplied, an evaporator, 15
20 said sump tank and evaporator forming a closed circuit with a condenser and treating vessel, means for conducting solvent from said sump tank to said evaporator, means for supplying heat to said evaporator, means responsive to the rise of liquid in said sump tank to a predetermined level for simultaneously supplying current to said motor and for also decreasing the supply of heat to 20
25 said evaporator, and means responsive to the fall of liquid in said sump tank to a predetermined level for simultaneously cutting off the supply of current to said motor and increasing the supply of heat to said evaporator.

RUSSELL A. HETZER.
